UNITED STATES PATENT OFFICE.

MILTON K. LIGHT, OF WORCESTER, MASSACHUSETTS.

DESIGN FOR A BADGE.

SPECIFICATION forming part of Design No. 20,455, dated January 6, 1891.

Application filed November 24, 1890. Serial No. 372,538. Term of patent 7 years.

To all whom it may concern:

Be it known that I, MILTON K. LIGHT, a citizen of the United States, residing at Worcester, in the county of Worcester and State of Massachusetts, have invented and produced a new and original Design for a Religious-Society Emblem or Badge, of which the following is a specification, reference being had to the accompanying drawing, forming a part

10 thereof.

My design is for a religious-society emblem or badge; and the leading feature of my design consists in the original shape and ornamentation of the emblem or badge.

15 The drawing represents a front view of the emblem or badge, showing my design.

Referring to the drawing, 1 is the emblem or badge of my design, which is of the general shape and contour shown, having the 20 four projecting arms 2, which have the ap-

pearance of a Maltese cross, and the four star-points 3, extending between said arms 2, which have the appearance of a four-pointed star of pyramidal shape extending over the cross, and the circular or crown portion 5, 25 which has the appearance of extending over the star and the cross, and the central circular part 6, which has the appearance of being placed on the crown.

What I claim is—

30 A design for a badge, having a star-shaped figure formed of a four-armed cross with four star-points of pyramidal shape extending between said arms and a crown-shaped center, substantially as set forth.
